UNITED STATES PATENT OFFICE.

BENJAMIN F. BOOTH, OF INDIANOLA, IOWA.

STOCK-WATERING TROUGH.

No. 847,893.

Specification of Letters Patent.

Patented March 19, 1907.

Application filed March 12, 1906. Serial No. 305,552.

To all whom it may concern.

Be it known that I, BENJAMIN F. BOOTH, a citizen of the United States, residing at Indianola, in the county of Warren and State of Iowa, have invented a certain new and useful Stock-Watering Trough; of which the following is a specification.

The object of my invention is to provide a stock-watering trough of simple, durable, 10 and inexpensive construction of the class in which the water is automatically maintained at a predetermined level in the trough.

My invention consists in the construction, arrangement, and combination of the parts 15 of the automatic controlling-valve whereby the objects contemplated are attained, as hereinafter more fully set forth, pointed out in my claims, and illustrated in the accompanying drawings, in which—

20 Figure 1 shows a sectional view of a stock-watering trough connected to the supply-tank and provided with my improved regulating-valve device. Fig. 2 shows an enlarged sectional view of the valve device detached. The dotted lines illustrate the position of the valve and working parts when open. Fig. 3 shows an edge view of the float. Fig. 4 shows an inside face view of the valve-controlling arm and the spring for aiding in 25 holding the valve in a closed position, and Fig. 5 shows a detail sectional view illustrating the valve closed tightly against the valve-seat.

Referring to the accompanying drawings, 30 I have used the reference-numeral 10 to indicate the stock-watering trough.

11 indicates a cylindrical valve-chamber having at one end a flange 12 to be connected by screws 13 with the inner face of the stock-watering trough. On the other end of the valve-casing is a flange 14, at the upper end of which are two projections 15, formed with slots 16, for purposes hereinafter made clear, and near the lower end of the flange 14 are 40 the brackets 17 to receive the rock-shaft 18. Formed on the inner end of the valve-chamber is an annular shoulder 19, upon which is seated a cylindrical valve-seat 20, preferably made of rubber or other flexible material. 45 Its outer end stands spaced apart from the interior of the valve-chamber, so that when a cylindrical valve is forced against said outer end the material of the valve-seat may expand and be forced outwardly, as shown in 50 Fig. 5, to thereby form a tight-fitting seat for the valve. Fixed to the rock-shaft 18 is an

upwardly-projecting valve-arm 21, which is normally held inwardly away from the plate 14 by means of the spring 22, which has coils in its end portions surrounding the rock-shaft 18 and a loop 23 at its central portion engaging the arm 21. The ends of the spring are secured at 24 to the plate 14. The valve is indicated by the numeral 25, and is of cylindrical form and provided with a valve- 60 stem 26, pivoted to the valve-arm. The float for controlling the valve-arm preferably comprises a board 27 with a central opening 28 near one end. On the under surface of the board is a metal plate 29, having an 65 opening 30 in line with the opening 28 and designed to receive the upper end of the valve-rod 21. I pivotally and adjustably connect the float 27 with the lugs 15 by means of two screw-threaded rods 31, 70 screwed into the ends of the float 27 and having right-angled extensions 32 on their ends which are passed through the slots 16 of the lugs 15.

In practice I so arrange the float relative 30 to the lugs 15 that when the float is in an approximately horizontal position it will hold the valve-rod 21 in such position that the valve 25 will be tightly fitted against the valve-seat 20. The spring 22 serves to aid in 85 holding the valve to its seat. When the float 27 descends by gravity, it will permit the arm 21 to move toward the plate 14, as shown by dotted lines in Fig. 2, whereupon the valve 25 will be removed from its seat 90 and water permitted to enter the tank 10 until the float is raised by the water and by the aid of the spring. If it is desired to adjust the float so that the valve will be seated more or less firmly when the float is in a horizontal 95 position, this may be done by simply turning the screws 31, and none of the parts under water need be touched by the operator for this purpose. Furthermore, the entire float may be very readily and quickly removed by 100 turning the ends 32 of the screws 31 to an upright position and then elevating the float to a substantially vertical position and withdrawing the ends 32 through the slots 16; but so long as the ends 32 are in a horizontal 105 position the float cannot be removed or accidentally displaced.

Having thus described my invention, what I claim, and desire to secure by Letters Patent of the United States therefor, is—

1. A stock-watering trough, comprising a trough-body, a valve-seat connected there-

- with, a valve to close against the seat, a valve-stem connected therewith and projected into the tank-body, a rock-shaft pivotally supported within the tank-body below the valve, 5 an arm fixed to said rock-shaft and projected upwardly and inwardly, said arm having the valve-stem pivoted thereto, a spring having its ends coiled upon the rock-shaft and attached to the tank-body and formed with a 10 loop at its central portion to engage said arm and normally hold it inwardly with the valve closed against its seat and a float pivoted above the valve and in engagement with said arm designed when lowered to force the arm 15 outwardly as required to open the valve.
2. A stock-watering trough comprising a trough-body, a cylindrical valve-chamber formed with an annular shoulder near one end, a cylindrical flexible valve-seat mounted 20 in said shoulder and spaced apart at its outer end from the interior of the valve-chamber, a valve in the chamber, a valve-stem connected therewith and projected inwardly, a flange at the outer end of the valve-chamber to be 25 attached to the trough, a flange at the inner end of the valve-chamber formed with slotted lugs at its top, a rock-shaft mounted on the inner face of the inner flange near its bottom, a valve-arm fixed to the rock-shaft and pro- 30 jected upwardly and inwardly, a spring having coils on its ends and a loop at its central portion, said coils wound around the shaft and said loop engaging the valve-arm to yieldingly hold the valve-arm inwardly, said 35 valve-stem also connected to the valve-arm, a float to engage the upper end of the valve-arm, two screw-threaded rods having right-angled projections, seated in the outer end of the float with said right-angled projections passed through the slotted lugs to pivotally, adjustably and detachably connect the float to the inner flange.
3. A stock-watering trough comprising a trough-body, a cylindrical valve-chamber formed with an annular shoulder near one end, a cylindrical flexible valve-seat mounted in said shoulder and spaced apart at its outer end from the interior of the valve-chamber, a valve in the chamber, a valve-stem connected therewith and projected inwardly, a flange at the outer end of the valve-chamber to be attached to the trough, a flange at the inner end of the valve-chamber formed with slotted lugs at its top, a rock-shaft mounted on the inner face of the inner flange near its bottom, a valve-arm fixed to the rock-shaft and projected upwardly and inwardly, a spring having coils on its ends and a loop at its central portion, said coils wound around the shaft and said loop engaging the valve-arm to yieldingly hold the valve-arm inwardly, said valve-stem also connected to the valve-arm, a float formed with an opening near its outer end and with a metal plate at the under surface of the opening, said plate formed with an opening to receive the upper end of the valve-arm, two screw-threaded rods having right-angled projections, seated in the outer end of the float with said right-angled projections passed through the slotted lugs to pivotally, adjustably and detachably connect the float to the inner flange.

BENJAMIN F. BOOTH.
